UNITED STATES PATENT OFFICE.

HENRY PEARSON, OF SPRINGFIELD, MASSACHUSETTS, ASSIGNOR TO GEORGE A. DENHAM, OF BOSTON, MASSACHUSETTS.

HINGE.

No. 874,427.

Specification of Letters Patent.

Patented Dec. 24, 1907.

Application filed May 8, 1907. Serial No. 372,534.

To all whom it may concern:

Be it known that I, HENRY PEARSON, a citizen of the United States of America, residing at Springfield, in the county of Hampden and State of Massachusetts, have invented certain new and useful Improvements in Hinges, of which the following is a specification, reference being had therein to the accompanying drawing.

10 My invention relates to a hinge which has a clutch-member that is actuated by movement of a leaf of the hinge and which is so constructed that the clutch-member is held locked in its clutching position when a leaf 15 of the hinge is in proper position to effect such locking.

I show my new hinge in the accompanying drawings wherein:

Figure 1 is a side elevation, partly in section at line 1—1 of Fig. 2 of my new hinge showing it in use and with its clutch-member locked in interlocking position with a coöperating socket. Fig. 2 is a front plan view of the hinge when in the position indicated in Fig. 1. Fig. 3 is a view similar to Fig. 1, but showing the parts in inoperative position. Fig. 4 is a top plan view in section at line 4—4 of Fig. 1, of the hinge and shows the clutch-member in clutching position.

30 In the drawings, 1 is the lower and 2 the upper hinge-leaf, and 3 the pintle that connects them. A link 4 is pivotally connected at 5 to the leaf 2 and is pivotally connected at 6 to the clutch-member 7 which is pivotally connected at 8 to leaf 1, the pivotal connection at 6 being rearward of the pivotal

connection at 8 so that when the leaf 2 is swung on pintle 3, it will move link 4 and consequently swing the clutch-member 7 in one direction or the other. In its forward 40 position, the free end of the clutch member is in position to interlock with an exterior part, such as socket *b*, for example, in part *a*. The hinge is mounted on a part, such as *a'*, for example, that is to be interlocked with *a*. Preferably the coupling-member 7 (the free end of which may be of any desired shape) is provided with an abutment 9 which brings up against link 4 when the coupling-member is swung back into operative 50 position. The coupling-member is shown in the form of a hook with the rear side of its butt-end eccentric to the pivot at 8 so that the member is swung on pivot 8 by the thrust or pull given link 4, when leaf 2 is 55 moved. When leaf 2 is extended in the direction of leaf 1, the pivotal connection 5 is carried past pintle 3, and the coupling-member 4 is locked in its projecting or interlocking 60 position.

Having thus described my invention, what I claim and desire to secure by Letters Patent is:

The herein-described hinge, comprising a pair of leaves jointed together and combined 65 with a link and coupling member.

In testimony whereof I have affixed my signature in presence of two witnesses.

HENRY PEARSON.
